P. J. H. BERNARD,
PROCESS OF MANUFACTURING INSULATORS,
APPLICATION FILED DEC. 27, 1919.

1,340,813.

Patented May 18, 1920.

Inventor
Pierre J.H. Bernard

By *William Galister*

Attorney

UNITED STATES PATENT OFFICE.

PIERRE JOSEPH HENRI BERNARD, OF MONTREAL, QUEBEC, CANADA.

PROCESS OF MANUFACTURING INSULATORS.

1,340,813.

Specification of Letters Patent. Patented May 18, 1920.

Application filed December 27, 1918. Serial No. 347,757.

To all whom it may concern:

Be it known that I, PIERRE JOSEPH HENRI BERNARD, a subject of the King of Great Britain, residing at Montreal, Province of Quebec, Canada, have invented certain new and useful Improvements in Processes of Manufacturing Insulators; and I do hereby declare that the following is a full, clear, and exact description of the invention, such as will enable others skilled in the art to which it appertains to make and use the same.

The present invention has relation to a process of manufacturing insulators for electric heaters, and the principal object is to provide a device of the character set forth, that is capable of relatively great resistance, whereby a maximum degree of heat generation and subsequent radiation is assured.

A further object of the invention is to isolate the insulated sheets between convolutions of asbestos whereby the core tube is protected against the heat generated by the resistance element wound thereon.

Another object of the invention is to provide novel means for securing the insulating material upon the core tube.

With the above and other objects in view which will hereinafter appear as the description continues, the invention consists of the novel features of construction, combination and formation of parts as will be hereinafter more fully described and particularly pointed out in the appended claim.

In the accompanying drawings has been shown a simple and preferred form of the invention, it being, however, understood that no limitation is necessarily made to the precise structural details herein exhibited, but the right is hereby reserved to any changes, alterations or modifications to which recourse may be had that come within the scope of the claim without departing from the spirit of the invention or sacrificing the efficiency of the same.

In the drawings:

Figure 1 is a detail sectional view of the improved heater;

Fig. 2 is a perspective view of the core tube and mica and asbestos sheets, prior to the winding of the latter upon the tube;

Fig. 3 is a fragmental elevational view of

the heater illustrating the application of 55 the resistance element thereto; and,

Fig. 4 is a sectional elevation of one end of the heater.

In the embodiment of the invention illustrated in the drawings, the numeral 10 60 designates a hollow metallic tube having its end portions threaded as at 11 and 12, while end portion 12 is reduced as at 13 and such reduced portions 13 is threaded as at 14.

Several sheets of mica 15 are assembled 65 upon an outer sheet of asbestos 16 and the tube 10 is placed thereupon. Then the mica and asbestos sheets 15 and 16 are wrapped around tube 10 which forms the cylinder 17.

Rings 18 and 19 and nuts 20 and 21 are 70 screwed on the threaded end portions 11 and 12 of tube 10 and a plug 22 is screwed on the tube extensions 13. The plug 22 is exteriorly screw threaded as at 23 and carries a pair of oppositely disposed terminal posts 24 and 25 to which the lead wires may be attached in the usual manner.

The resistance element comprises relatively fine nichrome wire 26 which is wound in spaced relation upon the insulation cylinder 17. 80

Proper contact connections are made with the terminal posts 24 and 25 at one end of the cylinder, which at the opposite end of the wire 26 is in connection with tube 10 85 by means of a tap screw 27, which latter takes into the bore 28 thereof.

I have found that by the use of mica in sheets and the same enveloped by asbestos in the manner stated, the insulated cylinder 17 will consist of alternate layers of mica and asbestos.

The tube 10 is completely insulated from the resistance element 26 and the successive laminations of asbestos and mica is immune from the great heat generated thereby.

Having thus fully described my invention, what I claim as new and desire to secure by Letters Patent is:—

The method of manufacturing insulating cylinders which comprises wrapping the center tube in sheets of mica and asbestos in such manner that each layer of mica will be inclosed by a layer of asbestos.

In witness whereof I have hereunto set my hand.

PIERRE JOSEPH HENRI BERNARD.
